UNITED STATES PATENT OFFICE

147,468

DESIGN FOR AN AUTOMOBILE SERVICE STATION

Carl August Petersen, Wilmette, Ill., assignor to
The Pure Oil Company, Chicago, Ill., a corpora-
tion of Ohio

Application October 19, 1945, Serial No. 123,017

Term of patent 14 years

(Cl. D13—1)

To all whom it may concern:

Be it known that I, Carl August Petersen, a citizen of the United States, residing at Wilmette, in the county of Cook and State of Illinois, have invented a new, original, and ornamental Design for Automobile Service Station, of which the following is a specification, reference being had to the accompanying drawings, forming part thereof.

Descriptions of the figures are as follows:

Figure 1 is a front elevational view of the service station, showing my new design.

Figure 2 is a perspective, elevational view showing the front and one side of the service station; and

Figure 3 is a perspective, elevational view showing the rear and the side of the service station opposite to the side shown in Figure 2.

I claim:

The ornamental design for an automobile service station, substantially as shown.

CARL AUGUST PETERSEN.
